United States Patent Office

Des. 187,924

Patented May 17, 1960

187,924

LOUD-SPEAKER CABINET

Edward F. Shaver and Ralph P. Glover, La Grange Park, Ill., assignors to The Muter Company (Jensen Manufacturing Company Division), Chicago, Ill., a corporation of Illinois

Application April 27, 1959, Serial No. 55,672

Term of patent 14 years

(Cl. D26—14)

Fig. 1.

Fig. 2.

We claim:

The ornamental design for a loud-speaker cabinet, substantially as shown and described.
